UNITED STATES PATENT OFFICE.

HUGO E. BUECHNER, OF CHEYENNE, WYOMING.

DESIGN FOR A SPOON.

SPECIFICATION forming part of Design No. 22,545, dated June 20, 1893.

Application filed March 30, 1893. Serial No. 468,387. Term of patent 3½ years.

To all whom it may concern:

Be it known that I, HUGO E. BUECHNER, a citizen of the United States, residing at Cheyenne, in the county of Laramie and State of Wyoming, have invented a new and original Design for Spoons, of which the following is a specification.

The invention relates to a new and original design for spoons.

10 The object of the present invention is to provide an ornamental and attractive spoon; and the leading feature of the design resides in a spoon having a twisted stem terminating at the outer end in an ornamental socket, an 15 ornamental tip arranged in the socket and having an opening, crossed arrows arranged on the twisted stem and a representation of a lariat.

In the drawings—Figure 1 is a plan view 20 of a spoon showing my original design. Fig. 2 is a reverse plan view.

Referring to the drawings, 1 designates a

spoon having a twisted stem 2 and provided at the outer end of the stem with an ornamental socket 3. The stem has arranged on 25 it crossed arrows 4 and a representation 5 of a lariat. The tip 7 has an opening 6 and is arranged at the outer end of the stem at the socket 3. The socket 3 has a scalloped edge; and the tip 7 is of irregular oblong shape in 30 elevation.

It will be seen that the various features of the design impart to the spoon an ornamental and attractive appearance.

What I claim is—

35 The design for a spoon herein shown and described.

In testimony that I claim the foregoing as my own I have hereto affixed my signature in the presence of two witnesses.

HUGO E. BUECHNER.
